M. LEBEIS

MAGNETIC PHONOGRAPH

Filed June 3, 1922

Inventor:

Martin Lebeis

UNITED STATES PATENT OFFICE.

MARTIN LEBEIS, OF BERLIN-FRIEDENAU, GERMANY, ASSIGNOR TO TELEGRAPHIE-
GESELLSCHAFT MIT BESCHRÄNKTER HAFTUNG SYSTEM STILLE, OF BERLIN, GER-
MANY.

MAGNETIC PHONOGRAPH.

Application filed June 3, 1922. Serial No. 565,769.

To all whom it may concern:

Be it known that I, MARTIN LEBEIS, a citizen of the German Republic, residing at Berlin-Friedenau, Germany, have invented 5 certain Improvements in Magnetic Phonographs, of which the following is a specification.

The present invention relates to a phonograph of the kind in which the sound is recorded and reproduced magnetically by 10 means of a travelling steel wire or tape which is carried by two reels, and is unwound from one reel while it is wound up on the other reel, and consists in winding the wire 15 or tape on stationary reels by means of revolving winding-arms.

The arrangement has the advantage that, since only a very small portion of the wire is kept in motion, the momentum of the 20 moving parts will be small and easy to overcome so that the machine can be stopped and reversed almost instantaneously without jerks and excessive strains on the elements, which is essential, particularly when the apparatus is used for dictating purposes. There will thus be no difficulty connected 25 with the driving of the wire at the required speed, and any length of wire can be used without increasing the momentum of the 30 moving parts.

The accompanying drawings represents, by way of example, a sectional side-view of the improved apparatus.

The two stationary reels *a* and *a'* are 35 mounted rigidly, each by means of a hollow boss *d*, on a base board *i*. Rotatably held in each boss is a spindle *m* which carries at its upper end a bracket *n*. To each bracket is pivoted an arm *b* which is spring-supported 40 and which holds a pulley *s*. Another pulley *t*, carried by a separate arm on the bracket, is arranged above the spindle *m* and so is a rigidly supported guide pulley *u*. The record wire or tape *c* passes over the pulleys, 45 and can be wound on either reel by a rotary motion of the spindle *m*, in which the arm *b* participates. Between the pulleys *u* the wire passes through a magnet element *v* by means of which the sounds are recorded on 50 and reproduced from the wire.

Motion is imparted to the spindles in either direction by means of a revolving shaft *g* having two friction gears *k* with which to engage with friction gears *e* on the 55 spindles. The shaft *g* is adapted for axial

displacement so as to put either of said pair of gears into operation for winding the wire *c* on one of the reels, the other spindle being moved by the unwinding of the wire. The displacement of the shaft is effected by 60 means of a hand lever *f* which a spring *h* maintains in either end position.

When *c* is a wire it is necessary to reciprocate either the reels or the winding-arms axially in order to ensure a uniform 65 distribution of the coils on the receiving reel. For this purpose, the spindle *m* may be supported on cams or eccentrics *l* operated by means of suitable gears and by a shaft *r*. The latter receives its motion, through 70 the medium of a bevel gear *o*, from one of two bevel gears *p*, *q*, mounted on the shaft *g*. When the shaft *g* is adjusted, either for stopping the machine or for reversing the motion of the wire *c*, the motion of the cams 75 *l* is simultaneously stopped or reversed by the uncoupling of the gears *o*, *p* and *q*.

Should it be desired to wind the wire with greater speed on one reel than on the other, the gearing can be correspondingly altered. 80

I claim:—

1. In combination with the sound recording device of a magnetic phonograph, two stationary reels adapted to carry the record wire, each of said reels having a revolvably mounted winding arm associated therewith and adjacent thereto, means for guiding the record wire over the said winding arms, and means for independently positively actuating either of said winding arms, whereby 85 one of said winding arms is positively revolved to wind the wire upon its adjacent stationary reel and the other arm is free to revolve to permit the unwinding of the wire from its adjacent stationary reel. 90

2. In combination with the sound recording device of a magnetic phonograph, two stationary reels adapted to carry the record wire, each of said reels having a winding arm associated therewith and adjacent thereto, each of said arms being mounted upon a revoluble spindle, means associated with each arm for guiding the wire over it, and a driving shaft located intermediate said spindles and adapted to be operatively connected to either of them. 100

3. In combination with the sound recording device of a magnetic phonograph, two stationary reels adapted to carry the record wire, each of said reels having a revolvably 110

2
mounted winding arm associated therewith and adjacent thereto, means for guiding the record wire over the said winding arms, and means for independently positively actuating either of said winding arms, whereby one of said winding arms is positively revolved to wind the wire upon its adjacent stationary reel and the other arm is free to revolve to permit the unwinding of the wire from its adjacent stationary reel, and means for imparting a relative movement between each said winding arm and its reel in a direction along the axis of the said reel.

10 4. In combination with the sound recording device of a magnetic phonograph, two stationary reels adapted to carry the record wire, each of said reels having a winding

arm associated therewith and adjacent thereto, each of said arms being mounted upon a revolute spindle, means associated with each arm for guiding the wire over it, and a driving shaft located intermediate said spindles and adapted to be operatively connected to either of them, said spindles being longitudinally movable, each said spindle 25 having a cam associated therewith and adapted to be actuated by the movement of the said shaft, whereby each said spindle is simultaneously revolved and moved in a direction parallel to its own axis.

MARTIN LEBEIS.
